UNITED STATES PATENT OFFICE.

PETER DOSCH AND CHARLES R. DOSCH, OF STRATFORD, CONNECTICUT.

LUBRICATOR.

1,332,717.

Specification of Letters Patent. Patented Mar. 2, 1920.

Application filed November 14, 1918. Serial No. 262,447.

To all whom it may concern:

Be it known that we, PETER DOSCH and CHARLES R. DOSCH, both citizens of the United States, residing at the town of Stratford, county of Fairfield, and State of Connecticut, have invented certain new and useful Improvements in Lubricators; and we do declare the following to be a full, clear, and exact description of the invention, such as will enable others skilled in the art to which it appertains to make and use the same.

This invention relates to certain new and useful improvements in lubricators, and especially to a force feed type of lubricator for supplying lubricant to a multiplicity of bearings.

The primary object is to provide an efficient lubricator having a valved piston or plunger for controlling the intake and expulsion of the lubricant from its cylinder, and it consists primarily of a cylinder having plural discharge orifices at one end and a reservoir at the opposite end, a hollow plunger operable in the cylinder and provided with a lubricant passage in its head which is adapted to be closed by an actuating means for the plunger on the expressing stroke and to be opened on the return stroke.

The invention further resides in the features of construction and the association of parts hereinafter described in detail and claimed succinctly, the preferred embodiment being exemplified in the accompanying drawing wherein:

Figure 1, is a top plan view of the improved lubricator; and

Fig. 2, is a vertical section therethrough with the parts partly in elevation.

Further describing the invention, the construction illustrated embodies a reservoir 1, from which depends the cylinder 2, being in the present instance, integrally formed therewith and located at one end thereof. The lower end of the cylinder is closed by a head 3, having a plural number of discharge orifices into which the delivery pipes or tubes 4, are threaded.

Reciprocal vertically within the cylinder 2, is a downwardly facing plunger 5 having a long skirt portion and arranged diametrically in the upper opened end of the skirt portion is a vertical bail or plate like support 6, formed with a horizontal slot 7, within which latter is a circular cam 8 fixed on a transverse shaft 9, the shaft being

journaled in the side walls of the reservoir above the cylinder. One end of the shaft is extended and shaped to receive a handle 10 by which the cam may be rocked for vertically reciprocating the plunger.

The head of the plunger is provided with an oil passage or port 11 that extends through a packing ring 12, and a clamping ring or plate 13 serves to hold the packing 60 in place for which purpose screws 14 are employed. Within the plunger is a diametrical guide bracket 15, having a vertical guide opening through which slides the vertical stem 16 of a valve 17, said stem 70 extending through the lubricant passage 11, and carrying the valve on its lower end. The opening in the clamping ring is sufficiently large to receive the valve to permit the same engaging on its seat 18 provided by 75 the exposed portion of the packing ring.

Fixed on the transverse shaft 9 adjacent to the cam 8, is a second cam 19, of semi-circular form, which cam 19 is concentrically disposed relative to the shaft and 80 adapted to ride on the upper end of the valve stem. A coil spring 20 encircles the stem and seats at its lower end on the guide bracket or cross-bar 15, while its upper end is connected to the stem through the intermediary of the bearing ring 21, and cotter pin 22.

In operation, the cover plate 23 is first removed and the reservoir filled with lubricant, whereupon the handle 10 is rotated 90 from a vertical position, in which the oil passage through the plunger is closed by the valve, to the position in which the valve is open, as shown in Fig. 2. This movement will cause the plunger and its valve 95 to move in unison a short vertical distance when the valve stem will abut the concentric edge of the half cam 19, which stops the upward travel of the valve while the eccentric cam 8 has sliding contact on the 100 upper and lower sides of the slot 7 and continues to pull the plunger upwardly away from the valve. This relative movement affords an increased area for the flow of the lubricant through the plunger passage 11. Upon reverse movement of the handle the plunger is given an initial downward movement before the valve engages its seat. Continued manipulation of the handle in the reverse direction causes the 110 plunger and valve to move together and consequently to express and expel the

trapped lubricant therebeneath through the discharge orifices and tubes to the various bearings to which the tubes are connected.

In this connection it is to be noted that 5 the valve seats and commences its expressing movement with the plunger before the valve stem has reached the end of the concentric cam edge, whereby when the stem is caused to reengage the latter, on upward 10 movement of the plunger, the shoulder terminal of said edge will have passed and therefore the return operation of the stem will be free and unhindered. The valve is not greater in thickness than the clamping 15 ring so that full movement of the plunger down onto the orificed head is unobstructed. The quantity of lubricant supplied the bearings may be varied by adjusting the concentric cam 19 relative to cam 8, for 20 such adjustment will vary the time of opening and closing of the valve.

What is claimed is:—

1. In a force feed lubricator an oil reservoir, a cylinder communicating at one end 25 with the reservoir and having a plurality of discharge orifices in its opposite end, oil delivery tubes connecting with the orifices respectively and each extending to a part to be lubricated, a hollow plunger within the 30 cylinder having an oil passage in its lower end, a valve controlling said passage provided with an upwardly extending stem, a cam shaft, a cam thereon for operating the plunger, and means upon the shaft engaging 35 with the stem for actuating the said valve at predetermined times during the rotation of the shaft.

2. A self-contained lubricator embodying an oil reservoir, a cylinder rigidly attached 40 to the reservoir and communicating at one end with it and having a plurality of discharge orifices in its opposite end, each adapted to receive an oil delivery tube, a hollow plunger within the cylinder having 45 an oil passage in its lower end, a valve controlling said passage provided with an upwardly extending stem, a cam shaft, journaled on said reservoir, a cam thereon for operating the plunger, means upon the shaft 50 engaging with said stem for actuating said valve at predetermined times during the ro-

tation of the shaft, and means upon the exterior of the reservoir for manually oscillating the said shaft.

3. In a force feed lubricator, a cylinder 55 having one end communicating with a lubricant reservoir and its opposite end closed by a head having discharge orifices, a plunger operable in the cylinder, a packing member, a clamping member securing the 60 packing on the head of the plunger, said packing and plunger being formed with an oil passage and said clamping member having an opening of larger diameter than the oil passage whereby to expose a portion of 65 the packing to function as a valve seat, and a valve engageable with the seat.

4. In a force feed lubricator, a cylinder having one end communicating with a lubricant reservoir and its opposite end closed 70 by a head having discharge orifices, a plunger operable in the cylinder, a packing member, a clamping member securing the packing on the plunger head, said packing and plunger being formed with an oil passage 75 and said clamping member having an opening of larger diameter than the oil passage whereby to expose a portion of the packing to function as a valve seat, a valve engaging the seat, and means for simultaneously operating the plunger and valve.

5. In a force feed lubricator, a reservoir, a cylinder communicating therewith at one end and having its opposite end formed with discharge orifices, a plunger operable 85 in the cylinder and formed with an oil passage, a valve controlling said passage and having a stem extending upwardly therethrough, a bail extending upwardly from the plunger, a cam shaft carrying a cam co-operable with the bail to actuate the plunger, and a second cam engageable with the valve stem for controlling the opening of the valve.

In testimony whereof we affix our signatures in presence of two witnesses.

PETER DOSCH.
CHAS. R. DOSCH.
